UNITED STATES PATENT OFFICE.

DUNCAN McLOCHLAND QUARLES, JR., OF HOWELL, KENTUCKY.

PERMUTATION-LOCK.

SPECIFICATION forming part of Letters Patent No. 447,519, dated March 3, 1891.

Application filed October 16, 1890. Serial No. 368,281. (Model.)

To all whom it may concern:

Be it known that I, DUNCAN McLOCHLAND QUARLES, Jr., a citizen of the United States, residing at Howell, in the county of Christian 5 and State of Kentucky, have invented a new and useful Permutation-Lock, of which the following is a specification.

This invention relates to permutation-locks; and the object of the same is to effect improvements upon locks of this character heretofore existing.

To this end the invention consists of the details of construction hereinafter more fully described and claimed as new, and as illustrated in the drawings, in which—

Figure 1 is a rear elevation of the interior of my improved lock, showing the parts as locked. Fig. 2 is a similar view when the parts are unlocked. Figs. 3, 4, 5, and 6 are 20 perspective details respectively of the connecting-lever, the two slides, the notched lever, and the pin-lifting plate. Fig. 7 is a perspective detail of the slab-box, the two stop-bolts therein, one of them raised, and the right and 25 left main levers connected with said bolts. Fig. 8 is a plan view of the lock as shown in Fig. 1. Fig. 9 is a plan view of the right spindle with the outer two tumblers removed. Fig. 10 is an elevation of the end of the spindle 30 shown in Fig. 9. Fig. 11 is a perspective detail of one tumbler removed, showing its face detached and illustrating its movable hub. Fig. 12 is an elevation of the inner face of 35 the inner right-hand tumbler, showing the notched lever which is operated thereby. Fig. 13 is a diagrammatic view illustrating one of the dogs and showing in dotted lines a tumbler, its pin, and the lever-support. Fig. 14 is a similar diagram showing the tumbler as being turned in the wrong direction.

Referring to the said drawings, 1 is the door of a safe or vault; 2, the lock-case secured to the inner face thereof; 3, the locking bolt or bolts; 4, a rod connecting said 45 bolt with a crank-wheel 5, and 6 the shaft of a bolt-operating knob, all of which are of the usual or of any preferred construction and form no part of the present invention.

In the drawings the rear face-plate and the 50 top plate of the lock-casing 2 are shown as removed in order to permit the mechanism of the lock to be seen; but it will be understood

that in the finished lock these plates are of course in place. I have not illustrated the dials having graduations and the knobs for 55 operating the same, as these are well understood and as they are located upon the face of the safe-door and are keyed upon shafts extending through the lock-casing in the ordinary manner, and while the dials and knobs 60 would not be seen in the views presented in the drawings the shafts 7 and 8, extending from them, are seen and represent, respectively, the right and left hand dials.

Keyed upon each dial-shaft is a gear-wheel 65 10, which meshes with another gear 11, mounted loosely upon right and left hand spindles 12 and 13, and by this means the turning of a dial causes the rotation of a gear 11, and also of all of the tumblers, which, with said 70 gear, are loosely mounted upon the spindle, while the necessity for making the spindle tubular and extending the dial-shaft through the same with the dial on one end and the gear 10 on the other is avoided. Upon each 75 spindle is mounted a number of tumblers 14, (only three being shown in the present instance,) and outside the outermost tumbler a cam 15 is also mounted loosely on the spindle, but is rigidly connected to the inner face 80 of the gear 11. This cam has a beveled face 16 and a hook 17, for a purpose to be described hereinafter, and the inner face of the cam and the adjacent faces of the tumblers are provided with interlocking pins, as is usual in 85 locks of this character, and whose functions will be understood without more explicit description.

Referring now to Figs. 9, 10, and 11, each spindle is preferably reduced in diameter in 90 the shape of steps from its inner to its outer end, and upon each step is mounted a tumbler 14, a washer 20 being interposed between this tumbler and the next, and preferably provided with studs 21, taking into grooves 22 in 95 the steps in order to prevent the turning of the washers as the tumblers rotate, which would tend to undesirably affect the adjacent tumblers. Each tumbler 14 consists of an annular body having a large hub 23, provided with 100 an annular tongue 24, which engages between the two outer plates 25 of the tumbler. The rearmost plate is rigidly connected to the body of the tumbler, but the front plate is re-

movable, as seen in Fig. 11, bolts or screws 26 connecting the several parts of the tumbler-body. In openings 27 at opposite sides of the hub 23 are located springs 28, which 5 bear upon the periphery of the hub and hold the same by friction against rotation within the annular portion of the tumbler. Each tumbler is provided with a notch 29 for the reception of the lever-support 30, as is usual, 10 and the interlocking pins above referred to are seated in the hubs 23, as shown.

When it is desired to change the combination of this lock, the main levers 36 and 37 are pushed forward, each in the proper direction, until the pins 35 on the rear of said levers and the notches 34 in the outer faces of lever-supports 30 have become disengaged. Then main levers 36 and 37 can be raised until they will rest on top of lever-supports 20 30 by means of pins 35, thereby raising hooks 38 of main levers 36 and 37 high enough to prevent their engagement with hooks 17 of cams 15 when said cams are turned. Then the dials can be turned, causing cams 15 to 25 turn. Then it will be plainly seen that as the cams 15 turn hubs 23 will turn also by means of the interlocking pins described above, this movement of course altering the relative arrangement and location between 30 said pins and the notches 29 in the rims of the tumblers, said rims being held stationary by the tip of lever-support resting in the notches 29. Hence the dial must be thereafter differently manipulated to bring the several notches 29 successively beneath the tip 35 of the lever-support. Each lever-support 30 is of approximate L shape, pivoted at 31 to the casing 2, having a slot 32 engaging a pin 33 to limit its movement, extending outwardly over the tumblers 14 and having a 40 notch 34 in its outer face, as shown. This notch is adapted to receive a pin 35 on the rear face of the right and left main levers 36 and 37, and the free ends of said levers are 45 also provided with hooks 38, adapted to engage hooks 17 of the cams 15, and with shoulders 39, adapted to pass over the rounded faces of said hooks 17, as hereinafter described.

50 40 41 are bell-crank levers mounted upon shafts 42 through the casing, and the main levers 36 and 37 are respectively pivoted to the upper ends of arms 43, rising from the bodies of these levers. To other arms 44, 55 also extending from said bodies, are pivoted links 45, whose lower ends are in turn pivoted to stop-bolts 46, moving vertically in a powerfully-constructed slab-box 47 across the rear end of the locking-bolt 3 when the latter 60 is shot. When the safe is locked, these stop-bolts prevent the retraction of the bolt, as will be clearly understood; but when the tumblers are turned so that the hooks 17 engage the hooks 38 and draw upon the main levers 36 and 37 it will be understood that the bell-crank levers 40 41 are turned and the stop-bolts 46 raised out of the slab-box. The bolt- 65

operating knob is then turned, which rotates shaft 6 and crank-wheel 5. The rod 4 is drawn upon and the bolt 3 moved inwardly into the 70 space just occupied by the stop-bolts.

50 is a standard rising within the casing 2, and to the upper end of this standard is pivoted what I shall term the "connecting-lever" 51, having a downwardly-extending face 52, 75 adapted to engage the notches 29 of the right-hand bank of tumblers. Pivoted to this lever is a link 53, and pivoted to this link is a connecting-bar 54, connecting it with an arm 55, rising from the left bell-crank lever 41; also, 80 pivoted to the link 53 is a weighted pawl 56, having a groove 57 in its lower face near its heavier free end. This groove slides upon a slide 60, which moves in brackets 61, and said slide has a notch 62 near one end, into which 85 the lower end of link 53 is adapted to drop when the face 52 of the connecting-lever 51 drops into the notches of the several tumblers and permits the link to descend a sufficient distance. Near the other end of the 90 slide 60 a bracket 63 rises therefrom, and has an open-topped notch 64 in its upper end. Through the slide 60 moves a pin 65, whose lower end rests upon a plate 66, pivotally connected at one end to the casing and riding 95 at its other end over a cam or lug 67 upon the body of the right-hand bell-crank lever 40.

In addition to the notched slide 60 a slide 70 moves in the brackets 61, and pivoted in an ear 71 of this slide is a latch 72, carrying an 100 outwardly-projecting pin 73, adapted to engage said open-topped notch 64, and also carrying a stud 74.

75 is a lever pivoted at one end to the casing, working behind the rearmost of the right-hand bank of tumblers, and having along its free end a flange 76, provided with a notch 77, which notch is adapted to pass over said stud 74 when the parts are relatively in the proper position. The right-hand bank of 110 tumblers being now turned to bring the notches 29 all beneath the face 52, the link 53 engages the notch 62 in the notched slide. The left-hand bank of tumblers is now manipulated until the hooks 17 and 38 engage, 115 the bell-crank lever 41 is rotated, the arm 55 is moved, the connecting-bar 54 is drawn upon, and the link is moved. This movement moves the notched slide 60, and through its bracket 63 the notch 64 therein, and the pin 120 73. The latch 72 may be moved by the rotation of the left-hand dial until the stud 74 exactly registers with the notch 77 in the flange 76. One of the notches 29 in the right-hand bank of tumblers has a beveled edge, 125 as shown at 29', and after the above movements the right-hand dial is turned to force this beveled edge under the face 52, and thereby to lift the connecting-lever 51, disengage the link 53 from the notched slide 60, 130 and thereby interrupt all connection between the left-hand dial and the right. The right-hand bank of tumblers is now manipulated to bring the notches beneath the lever-sup-

port 30, which, falling thereinto, permits the lever 36 to be moved by the engagement of the hooks 17 and 38. The right-hand dial is then turned, whereby the bell-crank lever 40 is operated and one of the stop-bolts 46 is raised. The same movement turns the cam 67 from beneath the plate 66 and allows the pin 65 to descend in the hole through the slide 60, so that its upper end no longer engages the end of the weighted pawl 56. The left-hand bank of tumblers is now further turned to raise the other stop-bolt 46, after which the locking-bolt 3 can be retracted in the usual manner. There are therefore four movements necessary to unlock this lock, first, to turn the right bank, drop the face 52 and engage the link 53 with the notch 62, thereby connecting the bell-crank lever 41 with the two slides; second, turning the left bank so as to move the slides and bring the stud 74 in register with the notch 77; third, again turning the right bank so as to bring the notches 29 under the lever-support 30, which by dropping, allows the lever 36 to be drawn upon and one of the stop-bolts to be raised; fourth, further turning the left dial to raise the other stop-bolt. It will be noticed that if the operator should omit to adjust the stud 74 and notch 77 in register with each other, when the right bank or dial was turned, the pin 80 on the innermost tumbler 14, which always strikes the lever 75, would raise this lever and also raise the stud 74, which then rested upon the flange 76, the result being that the latch 72 would be raised against the lower side of the lever-support 30 near its pivot. As a result, when during the third movement above described all the notches 29 have been brought beneath the lever-support 30 and the latter is ready to drop thereinto, it will not do so because the support is held up by the latch 72, as above stated.

In addition to the above devices I provide two dogs 81, pivotally connected to the lock-casing 2 behind the two banks of tumblers, each dog having a pointed extremity 82 and a weighted lower end 83, whereby it will normally maintain an upright position, and being so pivoted that when in this upright position it will stand beneath the lever-support 30 and prevent the same dropping into the notches 29 in the different tumblers, even if they should be immediately below. Pins 85 are seated in the faces of the innermost tumblers at such points that when the tumblers are rotated, each in its proper direction, the pins will strike the weighted bodies of the dogs and tip them to one side just as the notches in the innermost tumblers come underneath the lever-supports. If, however, the tumblers are turned in the wrong direction, it will be obvious that the notches therein will pass beneath the lever-supports before the pins 85 engage the dogs, and consequently at the moment the notches are beneath the lever-supports the pointed extremities 82 of the dogs would prevent the descent of the le-

ver-supports and the consequent operation of the main levers 36 and 37.

What is claimed as new is—

1. In a permutation-lock, the combination, with a spindle 12, having a number of steps provided with grooves 22, of tumblers 14, mounted one upon each step and having interlocking pins on their adjacent faces, and washers 20 between the tumblers, having inwardly-projecting studs 21 engaging said grooves, substantially as described. 70

2. The herein-described tumbler for permutation-locks, the same comprising a body 80 with a notch in its edge, a hub 23, turning within said body and carrying pins at each end engaging with those on adjacent hubs, and springs 28, located in recesses 27 of the body and bearing frictionally against the periphery of said hub, substantially as described. 85

3. In a permutation-lock, the combination, with a bank of tumblers having notches 29 and the inner tumbler having a pin 85, and 90 the lever-support 30, adapted to drop into said notches when they register, of a dog 81, centrally pivoted to the lock-case below said lever-support, its upper end 82 being reduced and its lower end 83 weighted, said pin 85 95 striking the weighted end of the dog and tripping its reduced end from beneath the lever-support when the tumbler is moved in one direction, as and for the purpose set forth. 100

4. In a permutation-lock, the combination, with the lever-support 30, the pivoted latch 72 beneath said support, means for moving the latch longitudinally, and a stud 74 on the latch, of a bank of tumblers, the innermost 105 one having a pin 80, a lever 75, pivoted to the casing and struck by said pin, and a flange 76, having a notch 77 adapted to move over said stud, as and for the purpose set forth. 110

5. In a permutation-lock, the combination, 115 with the lever-support 30, the latch 72 beneath said support, said latch having a stud 74 and a pin 73, the moving slide 70, to which said latch is pivotally connected, the moving slide 60 adjacent thereto and having a notch 62, the bracket 63, on said slide 60, having an open-topped notch 64 engaging said pin, the connecting-lever 51, mounted on a fixed pivot at one end and having a depending face 52 at its other end, adapted to engage the notches 29 of a bank of tumblers, the link 53, pivoted to said lever and having a reduced lower end removably engaging said notch 62, and means for moving the link around its pivot, of a bank of tumblers, the innermost one having a pin 80, a lever 75, pivoted to the casing and struck by said pin, and a flange 76, having a notch 77 adapted to move over said stud 74, as and for the purpose set forth. 120

6. In a permutation-lock, the combination, with the lever-support 30, the latch 72 beneath said support, said latch having a stud 74 and a pin 73, the moving slide 70, to which said

latch is pivoted, the moving slide 60 adjacent thereto and having a notch 62, the bracket 63 on said slide 60, having an open-topped notch 64 engaging said pin, the connecting-lever 51, mounted on a fixed pivot at one end and having a depending face 52 at its other end, adapted to engage the notches 29 of a bank of tumblers, the link 53, pivoted to said lever and having a reduced lower end removably engaging said notch 62, a bell-crank lever 41, a bank of tumblers, a main lever 37, connected at one end to said bell-crank lever and at its other end adapted to engage the notches 29 of this bank, an arm 55 on said bell-crank lever, and a connecting-bar 54 between said arm 55 and the link 53 for moving the latter around its pivot, of another bank of tumblers, the innermost one having a pin 80, a lever 75, pivoted to the casing and struck by said pin, and a flange 76, having a notch 77 adapted to move over said stud 74, as and for the purpose set forth.

7. In a permutation-lock, the combination, with the lever-support 30, the movable latch 72 beneath said support, said latch having a stud 74, the moving slide 60 adjacent the latch, connections, substantially as described, between the slide and the latch, the connecting-lever 51, mounted on a fixed pivot at one end and having a depending face 52 at its other end, adapted to engage the notches 29 of a bank of tumblers, the link 53, pivoted to said lever and having a reduced lower end removably engaging a notch 62 in said slide, and means for moving the link around its pivot, of a bank of tumblers, the innermost one having a pin 80, a lever 75, pivoted to the casing and struck by said pin, and a flange 76, having a notch 77 adapted to move over said stud 74, as and for the purpose set forth.

8. In a permutation-lock, the combination, with the lever-support 30, the movable latch 72 beneath said support, said latch having a stud 74, the moving slide 60 adjacent the latch, connections, substantially as described, between the slide and the latch, the connecting-lever 51, mounted on a fixed pivot at one end and having a depending face 52 at its other end, adapted to engage the notches 29 of a bank of tumblers, the link 53, pivoted to said lever and having a reduced lower end removably engaging a notch 62 in said slide, a bell-crank lever 41, a bank of tumblers, a main lever 37, connected at one end to said bell-crank lever and its other end adapted to engage the notches 29 of this bank, an arm 55 on said bell-crank lever, and a connecting-

bar 54 between said arm 55 and the link 53 for moving the latter around its pivot, of another bank of tumblers, the innermost one 60 having a pin 80, a lever 75, pivoted to the casing and struck by said pin, and a flange 76, having a notch 77 adapted to move over said stud 74, as and for the purpose set forth.

9. In a permutation-lock, the combination, 65 with the lever-support 30, the movable latch 72 beneath said support, said latch having a stud 74, the moving slide 60 adjacent the latch and having a notch 62, connections, substantially as described, between the slide and 70 the latch, the connecting-lever 51, mounted on a fixed pivot at one end and carrying a link 53, having a reduced lower end removably engaging said notch, and means for moving the link to reciprocate said slide, of a 75 bank of tumblers, the innermost one having a pin 80, a lever 75, pivoted to the casing and struck by said pin, and a flange 76, having a notch 77 adapted to move over said stud 74, as and for the purpose set forth. 8c

10. In a permutation-lock, the combination, with the lever-support 30, the movable latch 72 beneath said support, said latch having a stud 74, the moving slide 60 adjacent the latch, connections, substantially as described, 85 between the slide and latch, a bank of tumblers, and means for moving the slide from said bank, of another bank of tumblers, the innermost one having a pin 80, a lever 75, pivoted to the casing and struck by said pin, 90 and a flange 76, having a notch 77 adapted to move over said stud 74, as and for the purpose set forth.

11. In a permutation-lock, the combination, 95 with the bell-crank lever 40, having a cam 67 on its shaft, the stop-bolt 46, connected to one arm of said lever, a bank of tumblers, and a main lever 36, connecting said bank with the other arm of the bell-crank lever, of a plate 66, resting on said cam, a slide 100 60, connected to a latch 72, standing beneath the lever-support 30 of said bank, a pin 65, resting on said plate and passing loosely through a hole in the slide, a weighted pawl 56, having a groove 57 sliding over said slide, 105 and means for moving said pawl, as and for the purpose set forth.

In testimony that I claim the foregoing as my own I have hereto affixed my signature in presence of two witnesses.
